UNITED STATES PATENT OFFICE.

RUDOLF GOLDSCHMIDT, OF WESTEND, BERLIN, GERMANY, ASSIGNOR TO DET
TEKNISKE FORSØGSAKTIESELSKAB, OF CHARLOTTEBLUND, DENMARK, A
COMPANY OF DENMARK.

FLYING MACHINE.

Application filed January 11, 1921. Serial No. 436,513.

To all whom it may concern:

Be it known that I, RUDOLF GOLDSCHMIDT, a subject of the German Empire, and resident of 45 Linden Allee, Westend, 5 Berlin, Germany, have invented certain new and useful Improvements in Flying Machines, of which the following is a specification.

This invention relates to flying machines 10 wherein the supporting planes are reciprocated in a horizontal or substantially horizontal or slightly curved path and in which the angle of incidence of the planes may be automatically reversed during the change of 15 direction of movement of the planes.

The present invention relates more particularly to mechanism for reciprocating the planes as hereinafter more fully set forth.

According to the present invention the 20 mechanism for reciprocating the supporting planes in a horizontal or substantially horizontal or slightly curved path comprises centrifugal mechanism (such as that described in the specification of my United States Patent 25 No. 1,386,829) mounted to move with and reciprocate the planes, the centrifugal mechanism being preferably so mounted as to reciprocate to and fro on the body of the machine and being preferably also 30 adapted to automatically effect reversal of the angle of incidence of the planes during the change of direction of movement thereof.

In order that the invention may be clearly 35 understood reference is made to the accompanying drawings wherein:—

Figs. 1 and 2 are diagrams showing reversed angles of incidence of an aerofoil.

Fig. 3 is a diagram of a flying machine in 40 which the plane describes a slightly curved path of centre S.

Fig. 4 is a diagram illustrating a plane reciprocating in a straight path.

Fig. 5 is a detail view and Fig. 6 a fragmentary plan view of mechanism for reciprocating the plane shown in Fig. 4.

Figs. 7, 8, and 9 are diagrammatic views corresponding to Fig. 5 showing three different positions of the mechanism and Figs. 50 7^a, 8^a and 9^a are corresponding plan views thereof.

The planes reciprocate in a path which is substantially at right angles to the lift. In

Fig. 1 the supporting surface T moves substantially at right angles to the lifting force K with an angle of incidence α^1 , until the direction of movement is reversed as in Fig. 2, when the angle of incidence is also automatically reversed, changing from α^1 to α^2 as in Fig. 2 when the direction of motion 60 corresponds to arrow V¹ in Fig. 2. The angles of incidence α^1 and α^2 only apply if the direction of motion of the whole flying machine coincide with the direction of the motion of the planes. The lift depends 65 partly on the lifting action due to the angle of incidence of the planes and partly on the displacement of air by the reciprocation of the planes.

The actual velocity V¹ of movement of the 70 plane T relative to the machine and the velocity of flight V of the machine are substantially in parallel planes. In forward motion the lift is practically proportional to $(V^1 - V)^2$ whilst in return motion the lift is 75 practically proportional to $(V^1 - V)^2$. The former is therefore much more effective during flight and it is therefore preferable to thicken the front edge of the planes and to taper the trailing edge as in the usual aerofoil 80 section, the difference being probably somewhat less pronounced. If the planes are not only to generate a lifting force but also to propel the machine forwardly it may be desirable to use an aerofoil of symmetrical 85 profile.

By arranging the plane T as in Fig. 3 so as to reciprocate symmetrically on both sides of a plane M whilst describing a curved path of centre S, an oblique force 90 K is created which passes approximately through the line MS when the machine as a whole is stationary. A component Z is thereby obtained which may act as a tractive force and thus propel the machine forwardly. All the forces coincide at S which may be assumed to be the centre of gravity.

The tractive force Z and consequently the velocity of flight may be varied by varying the angle β which the plane M makes 100 with the vertical, that is to say, by varying the line on both sides of which the plane T symmetrically reciprocates. Alternatively the tractive force Z may be varied by the empennage control H.

Adjustment of the ascent and descent is 105

2
effected by variation of the angle of incidence or by variation of the velocity V , or by more or less throttling the motor. The tail fin N and the empennage control H serve 5 for longitudinal stabilization.

As an alternative construction, the forces K need not pass through the centre of gravity. The centre of gravity may be supposed to be as S^1 (instead of S). Then the 10 lift component A and the weight of the flying machine G^1 form a pair of forces which must be balanced by the tail fin N and the empennage control H . The moment will be however wholly or partly balanced by the 15 air resistance on external parts due to the fact that the centre of gravity lies comparatively deep below the planes and automatically becomes a correcting moment during longitudinal instability. Variation 20 of the radius $S S^1$ of the turning moment may be effected by displacing the centre S or by altering the centre of gravity of the flying machine. This variation involves regulation of the tractive force Z , since under 25 the influence of the turning moment, the flying machine turns and sets itself into a new stable tractive angle β .

The reciprocation of the movable planes on the flying machine body may be effected 30 in various ways. Fig. 4 shows a simple straight slipper guide. The guide bridge a is held by means of the struts b and tension wires c . The plane T slides on the bridge a by means of a slipper or carriage g . 35 Rollers may be used to diminish the friction. In this arrangement (as in Fig. 3) the lift A and weight G^1 of the flying machine form a pair of forces during forward motion.

40 In selecting the driving mechanism for the planes, it is to be noted that the period of one complete oscillation of the planes is only very short and may be only a fraction of a second and that, to accelerate and retard the masses, variable forces must be applied which are normally substantially greater than (for example) the whole lift. If these variable forces act at a point between the body and the planes, the whole 45 body of the machine as well as the planes will be set in vibration. The present invention therefore consists in providing a mechanism for driving the planes in such a manner as to avoid the aforesaid vibration of the body. For this purpose the 50 mechanism is of the type described in my prior United States Patent Specification No. 1,886,329.

55 Referring now more particularly to Figs. 5 and 6 of the accompanying drawings, a^1 and a^2 are guides forming a bridge for slippers g . The guides a^1 , a^2 are secured by the struts b^1 , b^2 , b^3 and b^4 and by the tension wires c^1 , c^2 , c^3 and c^4 . The slippers g support a vertical rod l to the upper end 60

of which the plane T is jointed at U . The rod l is interrupted by a bearing m for a sleeve x which carries two bevel wheels r^1 and r^3 . The sleeve x is splined on a driving shaft w so as to slide thereon but rotate therewith. As shown the shaft w is of square section. The sleeve x may however be driven by a flexible or telescopic shaft or the like or other convenient power transmission mechanism. Rotatably mounted on the rod l are two sleeves n^1 and n^2 and externally upon the sleeve n^2 is fitted a third sleeve n^3 . Fixed to the sleeves n^1 , n^2 and n^3 are rods S^1 , S^2 and S^3 respectively which carry at their outer ends 75 weights O^1 , O^2 and O^3 respectively. The weights O^1 and O^3 are connected together and together have about the same turning moment as the weight O^2 alone. In practical construction, probably considerably 80 more than three weights would be used. The sleeves n^2 and n^3 carry a pair of bevel wheels r^4 and r^2 respectively which engage with the bevel wheels r^3 and r^1 respectively. If the driving shaft w rotates the bush x and 85 the bevel wheels r^1 and r^3 , r^2 and r^4 , the weights O^2 and O^3 will be driven at the same rotational speed but in opposite directions. Thereby centrifugal forces s^1 and s^2 act on the rods S^2 and S^1 — S^3 the forces 90 being transmitted through the bearings n^1 and n^3 to the plane T .

The forces s^1 and s^2 form a resultant R (Fig. 6). In Figs. 7 to 10 and 7^a to 10^a other positions of the weights and parallelograms of forces relating thereto are indicated. It will be seen that R varies periodically and creates a to-and-fro movement of the planes. In Fig. 6 the supporting surface T moves under the acceleration of R 105 from right to left and attains its highest velocity in the position shown in Fig. 7 which corresponds to the plane M of Fig. 3. The forces s^1 and s^2 then balance each other. In Figs. 8 and 8^a the plane T has passed the 110 middle position. The forces S^1 and S^2 then give a negative resultant R retarding the movement of the plane T so that in the left end position (Fig. 9 and 9^a) the construction comes to a standstill in order, under the 115 force R , which is here equal to S^1+S^2 , to commence return motion. If A is the weight of the plane T and its accessories, without the swinging weights O^1 , O^2 and O^3 and B is the weight of the three weights 120 together, L the length of the arms S^1 , S^2 and S^3 and Z the displacement of the plane T in either direction, then for velocities 125 which are not too small:—

$$Z = \frac{2LB}{B+A}$$

If, for example, $B=A$, then $Z=L$. In any case Z is quite independent of the rotational velocity of the weights, provided that 130

the angular velocity is not altogether too small.

The plane is therefore positively reciprocated just as if it were driven with a crank and connecting rod of infinite length, but with many advantages as compared therewith. First of all, apart from lost components, at any instant, the centrifugal force R and the main accelerating forces exactly 10 balance each other. If it be so arranged, say by fitting a second supporting surface T¹ (Fig. 5) that the resultant force R acts at the centre of gravity of the movable parts, then the lifting force and part of the lost 15 components will be transmitted to the body of the flying machine. The actual lifting and driving mechanism with its large forces acts as a single unit in which the losses are made up by power from the driving shaft 20 w and in which the lift is taken up by the slippers g. By opposite rotation of the centrifugal weights the gyroscopic effect on the system is overcome.

The plane T in Fig. 3 may be reciprocated 25 by mounting the arms S¹, S², and S³ and the weights O¹, O² and O³ (Figs. 5 to 9) so as to turn about the line MS (Fig. 3) or by mounting the centrifugal mechanism in 30 any other convenient manner. When the plane T is carried by an arm pivoting about the point S in Fig. 3 and the weights turn around the arm in an analogous manner to that in which the weights turn about the shaft l in Fig. 5, the sleeve x of Fig. 5 may 35 be driven by a flexible shaft instead of the square shaft w (as already described with reference to Figs. 5 and 6) and the guides a¹, a² may be curved and concentric with the point S or the guides a¹, a² and slippers 40 g may be dispensed with.

It is easy to adjust the central plane of oscillation (M in Fig. 3). This may be effected by means of spring buffers p¹, p², p³ and p⁴ and adjustable stops h¹, h², h³ and h⁴. 45 The stops may be resilient instead of the buffers or both parts may be fitted with springs. The distances h¹—h² and h³—h⁴ are a little shorter than the displacement z, so that the buffer springs are easily 50 compressed. If the stops are shifted together forwardly or rearwardly, the centre plane M will be displaced as it lies approximately midway between h¹ and h², or h³ and h⁴. Thus a very effective control of the velocity 55 is attained.

The stability is ensured to a great degree in that the centre of gravity lies low beneath the lifting mechanism. For this reason warping surfaces or ailerons are not 60 necessary.

It may be mentioned that all sliding or rotating parts are preferably fitted with balls or rollers.

The angle of incidence can be adjusted 65 in many ways as for example by cranks, ec-

centrics or cams. Fig. 5 shows as a constructional example an eccentric e which is driven from the bush n¹. The eccentric e actuates the rollers f¹ and f² suspended from the plane T and thereby the plane is turned 70 about the joint U. The second plane T¹ (dotted in Fig. 5) can be separately adjusted or jointed to rigidly connect with T. Controllability of the angle of incidence in 75 operation for the purpose of varying the lift is important. In the arrangement illustrated in Fig. 5, for example, the rollers f¹ and f² could be made adjustable along their spindles so as to be moved across the surface of the eccentric e. Thus if the roller f¹ 80 is brought into contact with the lower edge of the eccentric and the roller f² in contact with the upper edge of the eccentric (that is, the reverse of that shown on the drawing) the roller f¹ will slightly tilt the plane 85 T about its joint U.

Claims—

1. In a flying machine of the character described, mechanism for reciprocating the planes comprising centrifugal mechanism 90 mounted to move with and reciprocate the planes.

2. A flying machine as specified in claim 1 in which the centrifugal mechanism is also so mounted as to reciprocate to and fro on 95 the body of the machine.

3. In a flying machine of the character described, a member carried by the body of the machine, centrifugal gearing slidably mounted on said member and a connection 100 between said gearing and the planes.

4. A flying machine as specified in claim 3 in which the member comprises a bridge-like structure mounted on the body of the machine.

5. A flying machine as specified in claim 1 in which the centrifugal mechanism also effects automatic reversal of the angle of incidence of the planes during change of direction of movement thereof.

6. A flying machine as specified in claim 1 in which the centrifugal mechanism comprises oppositely rotating centrifugal weights.

7. A flying machine as specified in claim 1 having means for varying the centre of reciprocation of the planes.

8. A flying machine as specified in claim 3 having adjustable buffers for variably controlling the travel of the centrifugal gearing.

9. A flying machine as specified in claim 1 in which the centrifugal mechanism comprises interconnected centrifugal weights and intermediate oppositely rotating weights.

10. In a flying machine of the character described a body structure, a longitudinally disposed guide carried by said structure, a slipper on said guide, means for limiting the travel of said slipper, a spindle supported 130

4

substantially vertically from said slipper, a supporting plane jointed to said spindle, centrifugal weights rotatable about said spindle, means for rotating said weights and means for reversing the angle of incidence of the supporting plane.

11. A flying machine as specified in claim

10 in which the centrifugal weights are interconnected to the means for effecting reversal of the angle of incidence so that reversal of the angle of incidence of the plane is effected during change of direction of movement thereof. 10

RUDOLF GOLDSCHMIDT.
